ADJUSTABLE SCREEN

Clarence H. Peterson, Oakland, Calif., assignor of
fifty per cent to George W. Peterson, Oakland,
Calif.

Application January 27, 1942, Serial No. 428,428

1 Claim. (Cl. 209—398)

This invention relates to new and useful improvements in sifting screens and more particularly to an adjustable screen.

The principal object of the present invention is to provide a screen, the mesh of which can be varied as the need demands.

Another important object of the invention is to provide an adjustable screen, the construction and use of which will save considerable time now consumed in making changes in equipment to take care of various sifting requirements.

Other objects and advantages of the invention will become apparent to the reader of the following description.

In the drawings:

Figure 1 represents a top plan view of the screen.

Figure 2 is a longitudinal sectional view through the screen taken substantially on the line 2—2 of Figure 1.

Figure 3 is a top plan view of the stationary plate of the screen.

Figure 4 is a fragmentary top plan view of the adjustable plate of the screen.

Figure 5 is a fragmentary top plan view showing the adjustable plate moved to a position for fine sifting.

Figure 6 is a longitudinal sectional view through the structure as adjusted to the position shown in Figure 5.

Figure 7 is an enlarged fragmentary detailed sectional view through the adjusting means.

Figure 8 is a section on the line 8—8 of Figure 7.

Figure 9 is a sectional view taken substantially on the line 9—9 of Figure 1.

Referring to the drawings wherein like numerals designate like parts, it can be seen that numeral 5 denotes a stationary plate of the sieve which has openings 6 at the edge portion thereof to receive screws, rivets or the like 7 which are disposed into the usual shaker frame (not shown). Thus, this plate 5 is stationarily secured.

The plate 5 has slots 7 at the corner portions thereof to receive bolts 8 which extend downwardly through openings in the corner portions of an adjustable plate 11. The bolts 8 are equipped with nuts 12.

One end of the stationary plate 5 has a rectangular-shaped opening 12 therein for receiving a yoke 13 depending from the adjacent end of the plate 11 and this yoke 13 embraces a reduced portion 14 of a screw shaft 15 which is feedable through a fixed nut 16 depending from the adjacent end of the plate 5. The screw shaft 15 has a polygonal wrench engageable head 17 at its outer end and carries a nut 18 which is feedable against

the yoke 13 to hold the screw 15 against self-adjustment.

As can be seen in Figure 3, the plate 5 is formed with a multiplicity of rows of square openings 19 extending obliquely or diagonally across the plate, from one end of the plate to the other and the edge portion of this area of openings 19 is filled in with small openings 20 each about one-fourth the area of anyone of the square openings 19.

10 The plate 11 is likewise formed with square openings 19a extending obliquely or diagonally across the plate and these openings 19a are approximately the same size as the openings 19. The difference with the arrangement openings of the plate 11 with respect to the plate 5, is that at one end of the plate 11 a string of small quarter size openings 20a are formed, so that when the plate 11 is shifted to the right with respect to the plate 5 in Figure 3, the openings 19a will be overlying the inner sections of the plate 5 between the openings 19 with the left endmost openings 19 of the plate 5 overlying the small openings 20a, thus the adjustment, which is shown in Figure 5 takes care of fine sifting.

25 While the foregoing specification sets forth the invention in specific terms, it is to be understood that numerous changes in the shape, size and materials may be resorted to without departing from the spirit and scope of the invention as claimed hereinafter.

30 Having described the invention, what is claimed as new is:

35 A screen for use on a shaker assembly comprising an oblong bottom plate adapted to be fixed on said frame, a similarly shaped top plate superposed on said bottom plate for endwise sliding movement longitudinally of the same, said bottom plate being provided with a rectangular area of squared openings therein arranged in longitudinal and transverse rows with the apertures aligned cornerwise in the rows, said top plate being provided with a similar sized area of similarly arranged openings, and means to slide said top plate into different set positions whereby the 40 openings therein may be variably registered with the openings in the bottom plate to form square screening openings of different sizes, the bottom plate having at one end thereof, a series of groups of smaller openings, said groups being so positioned that each group registers with one of the endmost rows of squared openings of said upper plate in one set position and each of said smaller openings being of substantially the same size as the screening openings formed by said squared 45 openings when the plates are in said set position.

CLARENCE H. PETERSON.
